MACHINE FOR WORKING SHOE UPPERS
OVER LASTS

Eric A. Holmgren, deceased, late of Beverly, Mass., by Gertrude A. Holmgren, administratrix, Beverly, Mass., and Harry B. Patten, deceased, late of Beverly, Mass., by Marjorie E. Patten, administratrix, Beverly, Mass., assignors to United Shoe Machinery Corporation, Flemington, N. J., a corporation of New Jersey

Application September 4, 1947, Serial No. 772,130

35 Claims. (Cl. 12—7.6)

1

This invention relates to machines for working shoe uppers over lasts, and is illustrated herein as embodied in a machine for pulling over the uppers of stitch-down shoes, a machine of that type being disclosed in United States Letters Patent 2,337,554 granted December 28, 1943, on an application filed in the names of E. A. Holmgren et al.

As in the machine disclosed in the above identified patent, the machine illustrated and described herein is provided with a support for the work which comprises a last having an upper and a sole member mounted thereon, and with grippers adapted to seize the margin of the upper. A relative movement between the support and the grippers heightwise of the last, for example, a heightwise movement of the support with relation to the grippers while the latter remain stationary and hold the margin of the upper, causes the upper to be pulled over the last. It has been found desirable, in organizations of the type above referred to, to insure that the upper not only is properly pulled over the sides of the last but also receives a positive pull in the longitudinal direction of the last toewards thereof and that the toeward pull be adjustable as to extent and intensity.

In accordance with one feature of the invention, therefore, the illustrated machine is provided, in addition to side grippers, with a toe gripper adapted to seize the margin of the toe-end of the shoe upper and to impart to the upper a lengthwise pull during and as a result of the relative movement between the work support and the toe gripper, mechanism being provided for adjusting the initial position of the work support from which the support starts its upward upper tensioning movement without, however, varying the final position at which the support terminates its upper tensioning movement. This results in the upper being positively tensioned in the longitudinal direction of the last in addition to being tensioned at the sides of the last, the longitudinally directed tension being variable or adjustable in extent and intensity. Thus, the work support may be adjusted in such a way that during its movement heightwise of the last it has a component of movement toeward or heelward of the last, or it may move heightwise of the last without such components of movement. As a result, the illustrated machine is capable of operating upon a large variety of sizes and styles of shoes, in effect larger than has been possible to operate

2

upon with any other machine of this or similar type heretofore known.

As in prior machines of the above identified type, the machine disclosed herein also is provided with mechanism adapted to clamp the margins of the upper and sole together after the upper tensioning or pulling-over operation and with additional mechanism for thereafter securing these margins together by fastening means such as staples. In accordance with another feature of the invention there is provided mechanism for releasing the toe gripper before the just mentioned clamping mechanism becomes operative and before the margins of the upper and sole are secured together. This release of the toe gripper in timed relation to the operation of the clamping and securing mechanisms just referred to mitigates against the possibility of the upper bridging over or spanning the usually slightly concave top-face of the last forepart.

Moreover, the illustrated machine is provided, as is common in machines of this type, with a toe gage mounted on the work support. In accordance with a still further feature of the invention there is provided adjusting mechanism common to the toe gage and toe gripper, which mechanism is adapted to effect the simultaneous adjustment of both the toe gripper and toe gage without affecting the mechanism for operating, that is for closing and opening, the toe gripper.

The mechanism above referred to for securing together the margins of the upper and the sole in the illustrated example comprises two stapling mechanisms. Each stapling mechanism has a stapling head and an anvil movable with relation to the head. In accordance with a further feature of the invention the stapling head is yieldingly moved to a predetermined position against a relatively fixed stop while the anvil is positively moved in a direction opposed to the movement of the stapling head to a predetermined position so as to clamp the margin of the upper and sole between the anvil and the stapling head. Thus, the stapling head, in view of its yieldable mounting, is adapted to accommodate varying thicknesses of the margins of the upper and sole to be operated upon. The stapling mechanism itself is adapted to form staples from a strand of wire fed into that mechanism and in accordance with still another feature of the invention there is provided a single actuating member adapted to move the anvil to clamp the margins of the sole and

upper against the stapling head and simultaneously to operate the wire feeding mechanism, thereafter to cause the fed-in extent of wire to be severed and a staple to be formed therefrom and then to operate a driver causing the latter to insert the staple through the margins of the upper and the sole and clinch it against the sole engaging face of the anvil.

These and other features of the invention will now be described with reference to the accompanying drawings and will be pointed out in the appended claims.

In the drawings,

Fig. 1 is a view in right-hand side elevation of a stitchdown shoe pulling-over and tacking machine embodying features of the present invention, the machine being shown partly in section and with certain parts removed;

Fig. 2 is a view in right-hand side elevation and on an enlarged scale of the work support and toe gripper of the machine illustrated in Fig. 1;

Fig. 3 is a section along the line III—III of Fig. 2;

Fig. 4 is a view in front elevation of mechanism for supporting and operating side units carrying the side grippers and the stapling mechanisms;

Fig. 5 is a section along the line V—V of Fig. 2;

Fig. 6 is a plan view of the work support with the work on it, as well as of the toe gripper and the side units;

Fig. 7 is a plan view of mechanism for adjusting the angular positions of the side units;

Fig. 8 is a view in front elevation of the mechanism shown in Fig. 7;

Fig. 9 is a sectional view of the rear portion of the work support;

Fig. 10 is a plan view of the rear portion of the toe gripper mechanism;

Fig. 11 is a sectional view, in front elevation, of the driving mechanism;

Fig. 12 is a detail view of part of mechanism for operating the side grippers and the stapling mechanisms;

Fig. 13 is a view in front elevation of one of the side units; and

Fig. 14 is a sectional view, in front elevation, of the upper portion of the side unit illustrated in Fig. 13.

As stated, the illustrated machine is adapted to pull over and secure by staples the upper of a stitchdown shoe, particularly a stitchdown shoe having a mid-sole to which the margin of the upper is lasted after the pulling-over operation and to which an outsole is secured thereafter, usually by stitches.

The shoe illustrated in Figs. 2, 6, 9 and 14 has an upper A and a mid-sole B both of which are mounted on a last C. The last C with the sole B and the upper A assembled thereon is supported in the machine on a work support 10 (Figs. 1 and 2) which, as will be described in detail, is at least in part carried by a bracket 12 secured to the machine frame 14. The machine is provided with side units 16 (Figs. 1, 6 and 13), there being two such units arranged at opposite sides of the forepart of the shoe when resting on the work support 10. Each side unit 16 comprises a side gripper 18 (Fig. 13) and a stapling mechanism 20. Moreover, there is provided a toe gripper 22 (Figs. 1, 2 and 6). The arrangement is such that after the work comprising the last C with the sole B and the upper A thereon has been placed on the work support 10, the marginal portion of the

upper at the forepart of the shoe is seized by the side grippers 18 and the toe gripper 22 whereupon the work support 10 is elevated while the grippers remain stationary, thus tensioning the upper over the last. Thereafter the marginal portion of the upper at opposite sides of the forepart of the shoe is caused to be clamped against the projecting margin of the sole by the side units which to this end have been moved into engagement with the opposite sides of the forepart of the shoe, thereby also firmly working the upper against the sides of the last and into the crease between the sides of the last and the margin of the sole. Finally the side units are caused to secure the margin of the upper to the projecting margin of the sole by staples inserted by the stapling mechanisms 20 which are associated with the side units.

To operate the various instrumentalities mentioned in the above brief introduction, the machine has a drive shaft 24 (Figs. 1 and 11) which is mounted in suitable bearings in the machine frame 14 and is driven from a conventional source of power. Secured on the drive shaft 24 is a worm 26 which is in meshing engagement with and drives a worm gear 28 mounted to rotate freely on a clutch shaft 30 rotatably mounted in the machine frame 14. The worm gear 28 is the driving member of a one-revolution clutch of the conventional type, the driven member 32 being fast on the shaft 30. The shaft 30 is provided on its left-hand side, as viewed in Fig. 11, with a brake mechanism of the conventional type which assists the one-revolution clutch in stopping the shaft 30 in a predetermined position after each revolution caused by an engagement of the clutch 28, 32. There is secured on the shaft 30 a gear 34 which meshes with a gear 36 secured on a cam shaft 38 also mounted to rotate in bearings provided in the machine frame 14. The ratio of transmission between the gears 34 and 36 is 2 to 1, that is to say, it takes two revolutions of the gear 34 to cause one revolution of the gear 36. Thus, during one revolution of the clutch shaft 30 only one-half revolution is imparted to the cam shaft 38 and in order to complete the rotation of the cam shaft 38 it is necessary to retreadle the machine and reengage the clutch 28, 32 to impart to the clutch shaft 30 a second revolution. Accordingly, the machine cycle is divided into two portions which are separated by a pause.

The clutch-tripping mechanism also is of the conventional type and comprises briefly a clutch-tripping plunger 40 (Fig. 11) which is actuated by the vertical arm (not shown) of a bell crank lever pivoted to the machine frame and having a horizontal arm 42 (Fig. 1) to which is pivotally secured a downwardly extending link 44. The lower end of the link 44 is pivotally connected, by means of a swivel block sliding on the link 44 and resting on stop collars, to an arm 46 secured on a rod or shaft 48 rotatably mounted in the machine frame 14. Fast on the shaft 48 is a downwardly extending arm 50 which is connected by a horizontal spring 52 to a fixed point on the machine frame. The spring 52, therefore, tends to swing the bell crank member comprising the arm 42 in a counterclockwise direction, as viewed in Fig. 1, to render the clutch inoperative. Secured to the shaft 48 is a horizontal arm 54 similar to the arm 46. The arm 54 is pivotally connected by means of a treadle rod 56 to a treadle 58 pivotally secured in the lower portion of the machine frame 14. The treadle 58 thus serves

to trip the clutch and to initiate the power operation of the machine. The tripping of the clutch is effected yieldingly in that a spring 60 is interposed between the above-mentioned swivel block, connecting the link 44 to the arm 46, and stop collars secured on the upper portion of the link 44. Depression of the portion of the treadle 58 extending outwardly from the machine frame thus results in a clockwise movement of the arms 54 and 46 against the tension of the spring 52 and in a yielding elevation of the link 44 and a clockwise motion of the arm 42 to trip the clutch 28, 32 which, in a manner well-known in the art, automatically becomes disengaged after the completion of one revolution. Obviously, on engagement of the clutch 28, 32 the clutch shaft 30 is driven and, as stated, each revolution of the clutch shaft 30 results in a one-half revolution of the cam shaft 38.

The cam shaft 38 actuates the various operating instrumentalities of the machine in proper time sequence by means of two cams mounted on that shaft. There is a cam disk 62 (Fig. 11) secured on the shaft 38, which cam actuates the toe gripper 22, the side grippers 18 and the work support 10 by means of different cam grooves provided therein as will be described. The other cam disk on the cam shaft 38 is the gear 36 which is provided in its opposite side faces with cam grooves as will be described, these cam grooves serving to swing the side units 16 into and out of engagement with the work and to actuate the stapling mechanisms 20.

To elevate the work support 10 for the purpose of pulling the upper over the last, the cam disk 62 (Fig. 11) has a cam groove 64 in its left-hand side, this cam groove being engaged by a roller carried on an arm 66 of a bell crank lever rotatably mounted on a shaft 68 secured in the machine frame 14.

The bell crank lever has a forwardly extending arm 70 (Figs. 1 and 11) which is connected by a long link 72 to the work support. Upward movement of the link 72, therefore, results in an elevation of the work support.

To close and open the toe gripper 22 there is provided a cam groove 74 in the right-hand side (Fig. 11) of the cam disk 62. This groove is engaged by a roller carried on an arm 76 of a bell crank lever freely rotatably on the shaft 68 and having a forwardly projecting arm 78 (Figs. 1 and 11) to the forward end of which is pivotally secured a trunnion block 80 mounted for sliding movement on a link 82 and normally resting against stop collars on the lower end of the link 82. A spring 84 surrounds the link 82 and rests with its lower end against the trunnion block 80 and with its upper end against fixed collars on the upper portion of the link 82. Accordingly, on clockwise motion (Fig. 1) of the bell crank lever comprising the arms 76 and 78, the link 82 is yieldingly elevated. The upper end of the link 82 is pivotally secured to a bell crank lever 86 rotatably mounted at 88 in the machine frame and this bell crank lever, in turn, is pivotally secured to and operates a forwardly extending link 90 which, as will be described in detail, serves to close and open the toe gripper 22.

To close and open the side grippers 18 there is provided another cam groove 92 in the right-hand side (Fig. 11) of the cam disk 62. The cam groove 92 is engaged by a roller carried on an upwardly extending arm 94 of a bell crank lever mounted to swing about a fixed shaft 96 and having another arm 98 which is pivotally con-

nected by a link 100 (Figs. 1 and 11) to a downwardly extending arm 102 of a yoke-shaped rocking member 104 (Figs. 1 and 12). The rocking member 104 is pinned on a shaft 106, mounted for rotation in the machine frame 14, and has two parallel, rearwardly extending arms 108 which have ball-and-socket connections with upwardly extending rods 110 adapted to operate the side grippers 18 at opposite sides of the work support.

To swing the side units 16 in and out with relation to the work support 10 and the shoe carried thereon, there is provided a cam groove 112 in the left-hand side (Fig. 11) of the gear 36. This cam groove 112 is engaged by a roller carried on an arm 114 mounted for rotation on the shaft 68. The arm 114 has a lateral projection 116 which is pivotally connected by a link 118 to an arm 120 (Fig. 1) pinned on a shaft 122 rotatably secured in the fixed bracket 12 of the machine frame 14. Secured to the shaft 122 is an upwardly extending arm 124 which carries at its upper end a bushing 126. The rearward end of a rod 128 extends through the bushing and is arranged for rotation in the bushing but is constrained to be moved endwise upon endwise movement of the bushing. The rod 128 has a threaded portion which is in engagement with a tapped bushing on the upper end of an arm 130. Upon initial operation of the arm 114 by the cam groove 112 the arms 120 and 124 are rotated in a counterclockwise direction (as seen in Fig. 1), thus imparting rotation in the same direction to the arm 130 which, as will be described in detail, causes both side units 16 to be swung into engagement with the work after the elevation of the work support 10.

To actuate the stapling mechanisms 20 associated with the side units 16 a cam groove 132 is provided in the right-hand side (Fig. 11) of the gear 36 and is engaged by a roller carried on an arm 134 of a bell crank lever mounted to swing on the shaft 96. The other arm 136 of the bell crank lever is pivotally secured to a forwardly extending link 138. The enlarged front end portion 140 (Fig. 1) of the link 138 has a horizontally extending slot 142 which is provided in its upper right-hand end portion with an upwardly extending small recess normally occupied by a pivot pin 144 carried by an arm 146 of a bell crank lever mounted for free rotation on the previously mentioned shaft 68. Thus, rearward movement of the link 138 as a result of the cam operation of the bell crank lever 134, 136 results in a counterclockwise swinging movement (Fig. 1) of the arm 146 about the shaft 68. The bell crank lever having the downwardly extending arm 146 has a horizontal, rearwardly extending web-like arm 148 (Fig. 12), this arm being located between the previously mentioned arms 108. The arm 148 has ball-and-socket connections with upwardly extending rods 150 which serve to operate the stapling mechanisms 20 associated with both side units as will be described in detail.

The provision of the slot 142 in the front end portion 140 of the link 138 is for the following purpose: Should it be desired, after the pulling-over operation and before the stapling operation, to render the stapling mechanisms inoperative, for example, if the operator is dissatisfied with the quality of the pulling-over operation and wishes to return the machine to its zero position to repeat the pulling-over operation and to avoid the driving of staples, the stapling mechanisms

are rendered inoperative by raising the front end portion 140 of the link 138, thereby causing the pivot pin 144 to enter the slot 142 proper with the result that on rearward movement of the link 138, the front end portion 140 moves idly and with relation to the arm 146, the latter thus remaining stationary and not operating the stapling mechanisms.

For the purpose of raising the front end portion 140 of the link 138 that portion is pivotally secured by an upwardly extending rod 152 to a bell crank lever 154 pivotally secured at 156 to the machine frame and connected to a forwardly extending link (not shown) located behind the link 118 in Fig. 1. This forwardly extending link is pivotally secured to an arm (not shown) corresponding to and located behind the arm 120 in Fig. 1 and being part of a bell crank lever freely rotatable on the shaft 122. This bell crank lever has a forwardly extending arm 158 to which is secured a handle 160. Accordingly, a depression of the handle 160 results in a swinging movement of the bell crank lever 154 in a clockwise direction as viewed in Fig. 1 and a raising of the front end portion 140 of the link 138, thus rendering the stapling mechanisms inoperative.

The timing of the operations of the various instrumentalities of the illustrated machine during the two portions of one cycle of operations as a result of the rotation of the cam shaft 38 is substantially as follows: During the first portion of a complete revolution of the cam shaft 38 corresponding to a complete cycle of operations, the toe gripper 22 and the side grippers 18 are closed upon the marginal portion of the upper about the same time by their respective mechanisms. While the grippers remain stationary and hold the upper, the work support 10 is elevated to perform the pulling-over operation and then the toe gripper 22 alone is opened. This completes the first portion of the cycle. During the resulting pause the operator now has an opportunity to inspect the quality of the pulling-over operation and, if satisfied, he initiates the second portion of the cycle by retreading the machine during which portion the side units are swung into engagement with the shoe. The marginal portion of the upper and the projecting margin of the sole are clamped together by the side units whereupon the side grippers are opened. Thereafter the stapling mechanisms are operated to drive staples through the clamped marginal portions of the upper and the sole, thus securing these portions together.

The above-mentioned work support 10 comprises a cradle-like member 162 (Figs. 1 and 2) which is supported at its front end by a swinging bracket 164 pivotally secured to the fixed bracket 12. At its rear end the cradle 162 is pivotally connected to and supported by the upper end of the above-mentioned link 72.

To support the rear portion of the work there is provided a U-shaped heel rest 166 (Figs. 1, 2 and 9), the two parallel arms of which are mounted to rotate on a pin 168 fixed in a boss 170 on a slide 172. The slide 172 is adjustable along a guideway provided in the upper portion of the cradle 162, the adjustment taking place in the longitudinal direction of the cradle 162.

To adjust the heel rest 166 heightwise of the cradle 162, so as to accommodate lasts of different springs (heel heights) and to insure that the forepart of the sole B is located substantially parallel to the upper portion of the cradle 162, the heel rest 166 has on its left-hand side, as seen

in Fig. 9, a downwardly extending arm 174 provided with a socket 176 in which is contained a spring-pressed plunger 178 carrying a hand knob. The inner end of the plunger is adapted to engage one of a series of holes 180 provided in a downwardly extending portion 182 of the slide 172, the holes being arranged along an arc drawn about the center of the pin 168. It will be seen that adjustment of the plunger 178 from one hole 180 to another results in a vertical adjustment of the work-engaging portion of the heel rest 166.

To adjust the heel rest 166 in the longitudinal direction of the cradle 162 so as to accommodate lasts of different lengths, the slide 172 is adjusted along the cradle 162. To this end the cradle 162 is provided with a T-shaped guide portion 184 (Fig. 9) which fits in a T-shaped guideway in the slide 172. The adjustment of the slide 172 in the longitudinal direction of the cradle 162 is effected by manual displacement of the slide. The slide 172 is locked in its adjusted position by a spring-pressed plunger 186 carrying a hand knob and contained in a socket member 188 secured to the side of the cradle 162, as best shown in Fig. 2. There are provided in the side of the slide 172 a series of rectilinearly arranged holes 190 into one of which the inner end of the plunger 186 enters so as to lock the slide 172 in its position of adjustment.

To support the forepart of the work there is secured to the cradle 162 a block 192 which may be termed a toe rest in that the toe portion of the sole B rests thereon (see Fig. 2).

There is furthermore provided a toe gage 194 (Fig. 2) which is in the form of a block slidable along a guide provided in the upper portion of the cradle 162. The guide corresponds to and may be considered a continuation of the guide 184 (Fig. 9). As will be described in detail, the toe gage 194 is connected to the toe gripper 22 and is adjustable with the latter in the longitudinal direction of the work support so as to accommodate lasts of different lengths. As shown in Fig. 2, the toe end of the last C abuts the toe gage 194.

It has been mentioned that the pulling-over operation is performed by an elevation of the work support 10 with the work on it while the marginal portion of the shoe upper A is held gripped by the toe gripper 22 and side grippers 18 which do not participate in that upward motion of the work support. Moreover, it has been stated that it is the power-operated link 72 which produces the upward motion of the work support. The initial position from which the link 72 starts its upward motion is adjustable whereas the final position of the link after having completed its upward motion is always fixed in the machine. Accordingly, the initial position of the work support from which it starts its upward motion is variable and the final position of the work support after the completion of the pulling-over operation is fixed in the machine. This means that the direction of upward motion of the work support is variable or, in other words, that in addition to its upward movement the work support has adjustable components of movement directed toward the toe end or the heel end of the shoe supported thereon. The adjustment of the initial position of the work support and, accordingly, the direction of the component of movement toewards or heelwardly is selected to suit the specific working conditions. With certain types of shoes a heelward component may be desirable;

with other shoes a toward component, and with still other types it may be most desirable to have no component of movement in either direction. The mechanism for bringing about this adjustment will now be described. There are mounted on the upper portion of the frame 14 spaced ears 196 (Figs. 1 and 5) which carry alined pivot studs 198. Rotatably mounted on these studs 198 is a yoke-shaped guide member 200 provided at the insides of its arm portions with guideways 202 (Figs. 2 and 5). Blocks 204 are movable along the guideways 202 and are pivotally mounted on the opposite ends of a horizontal pin 206 extending through, and fixed to, the link 72. During, and as a result of, the upward movement of the link 72 the blocks 204 are moved up in the guideways 202 until the pin 206 is alined with the axis of the studs 198. At this point the upward movement of the link 72 is terminated. The guide member 200 is adjustable about the pivot studs 198 when the link 72 occupies its initial lowermost position so as to vary the initial positions from which the link 72, as well as the work support 10, begin their upward motions. To this end the guide member 200 has a downwardly extending portion 208 (Fig. 2) which is pivotally connected by parallel links 210 to parallel arms 212 fast on a shaft 214 rotatable in the machine frame. The shaft 214 also carries an upwardly extending arm 216 provided with a spring-pressed plunger and hand knob 218. The plunger is adapted to engage one of a series of holes 220 provided in a block 222 secured to the machine frame 14. As will be readily seen, adjustment of the arm 216 along the block 222 results in a tilting of the guide member 200 about the axis of the pivot studs 198 and, accordingly, in a tilting of the guideways 202 along which the blocks 204 are constrained to move during the upward movement of the link 72. Since the pin 206 carrying the blocks 204, on termination of the upward movement of the link 72, is always positioned in alinement with the axis of the pivot studs 198, the adjustment of the guide member 200 does not vary the final elevated position of the work support.

The toe gripper 22 which is illustrated in Figs. 1, 2, 6 and 10 comprises a bar shaped main body 224 to which is fixed the lower jaw 226 of the gripper, whereas the upper jaw 228 is pivotally secured at 230 to the main body 224. The rear end of the main body 224 is fork-shaped, as illustrated in Fig. 10, and is pivotally secured by a pin 232 to the forked upper end of a swinging bracket 234 pivoted midway between its ends on alined, spaced studs 236 (Figs. 2 and 3) held in ears 238 (Figs. 1 and 3) provided on the upper portion of the machine frame 14. Moreover, there are provided a cover plate 240, which is secured to the top of the main body 224, and parallel side plates 242, the nearest one of which in Fig. 2 is shown broken off. As illustrated in Fig. 10 the inner faces of the rear ends of the side plates 242 are provided with grooves 244 in which are adapted to run supporting rolls 246, rotatable on the pin 232, on forward or rearward movement of the side plates 242 with relation to the main body 224 of the toe gripper. At their forward portions the side plates 242 are held together by a connecting pin 248 (Fig. 2) carrying a roller 250 which on forward or rearward movement of the side plates 242 rolls along the top face of the main body 224. There is another connecting pin 252 carrying a roller 254 which bears against the inclined tail portion 256 of the

upper jaw 228. Thus, on rearward movement of the side plates 242 with relation to the main body 224 of the toe gripper, the upper jaw 228 is moved toward the lower jaw to grip the marginal portion of the upper. The gripper is opened upon forward movement of the side plates. For thus moving the side plates 242 the already described power-operated link 90 is connected by a pin 258 (Fig. 3) to an arm 260. In the inoperative position of the machine parts as illustrated in Fig. 2 the pin 258 is positioned in alinement with the studs 236 (see particularly Fig. 3). The lower end of the arm 260 has pinned to it a stud 262, the opposite end portions of which are rotatably mounted in the lower end of the bracket 234. The upper end of the arm 260 is fork-shaped and carries rolls 264 which engage and are adapted to run in curved slots 266 cut into the enlarged rear ends of the side plates 242. The slots 266 are curved about the axis of the pin 232 as a center for a purpose to be presently described. The toe gage 194 has pivoted to it a yoke 268 through which is slidably a rod 270 carrying a spring 272. The lower end of the rod 270 carries a collar which prevents the rod from slipping out of the yoke 268. The upper end of the rod is pivotally mounted on the pin 232 inside of the upper end of the swinging bracket 234 (see Fig. 10). The just-mentioned spring 272 is confined between the yoke 268 and an enlargement on the upper end of the rod 270 (see Fig. 10). Thus there is a yielding connection between the toe gage 194 and the toe gripper 22 through which connection, upon adjustment of the toe gage to be described, the toe gripper will simultaneously be adjusted. The adjustment of the toe gripper 22 takes place without affecting the gripper closing mechanism. Thus if, for example, the toe gage 194 is adjusted toward the right of Fig. 2, the result is that the swinging bracket 234 is adjusted about the axis of the studs 236. Since the pin 258 connecting the power-operated link 90 with the gripper-operating arm 260 is located in alinement with the axis of the studs 236, the gripper-closing mechanism remains unaffected by this adjustment and any movement of the arm 260 caused by the swinging movement of the bracket 234 on adjustment produces merely an idle motion of the rolls 264 along the curved slots 266 in the rear portions of the side plates 242.

To adjust the toe gage 194 and the toe gripper 22 simultaneously, the toe gage is bolted to a rack bar 274 which is slidably mounted in the upper portion of the cradle 162 to move in the longitudinal direction thereof. With the rear portion of the rack bar 274 meshes a pinion 276 (Fig. 9) mounted on a stud 278 rotatably secured in the cradle 162 and extending outwardly from the cradle toward the right of Fig. 9. A locking sleeve 280, which is mounted for axial movement on and with relation to the outwardly extending portion of the stud 278 and which is splined on the stud 278 so that on rotation of the sleeve 280 the stud 278 is constrained to rotate therewith, carries a hand knob 282 on its outer end and a locking pinion 284 on its inner end. The locking pinion 284, in the normal inoperative position of the parts, meshes with a fixed rack bar 286 secured to the cradle 162. A spring 288 housed in the sleeve 280 and engaging with one end an internal shoulder of the sleeve 280 and with its other end lock nuts on a reduced portion of the stud 278 normally forces the sleeve 280 toward the left of Fig. 9 so that the locking pinion

284 and the fixed rack bar 286 are in meshing engagement and prevent rotation of the hand wheel 282. Adjustment of the toe gage and the toe gripper by a longitudinal displacement of the rack bar 274 is effected by pulling out the sleeve 280 toward the right of Fig. 9 and against the pressure of the spring 288 to move the locking pinion 284 out of engagement with the fixed rack bar 286 and then rotating the stud 278 by a rotation of the hand knob 282 and sleeve 280.

It will be understood that upon rotation of the cam shaft 38 the bell crank lever 86 is yieldingly rotated in a clockwise direction as viewed in Fig. 2 and that the link 90 is moved to the right of Fig. 2, swinging the arm 260 in a clockwise direction about the stud 262 which connects it to the swinging bracket 234. The swinging bracket, on closing of the toe gripper 22, of course, is stationary, it being normally stationary in the machine, and the only time it is moved is when the toe gage 194 is adjusted as described.

It has been stated that the side units 16 comprise each a side gripper 18 and a stapling mechanism 20. The side units 16 are illustrated in Figs. 1, 4, 6, 13 and 14. It also has been mentioned that on inward movement of the side units toward the shoe after the pulling-over operation the side units act as clamps by which the marginal portions of the shoe upper A and the sole B are clamped together. The location of the side units 16 with relation to a shoe on the work support 10 is illustrated best in the plan view of Fig. 6. In this view the units are shown as having engaged the work, that is to say, after they have been moved from their inoperative positions to their operative positions. It will be noted that the side units 16 at opposite sides of the shoe are located at different angles with relation to the longitudinal median line of the work support. The angular positions of the side units depend upon the so-called "swing" of the last, that is to say, the angle formed between the longitudinal median lines of the rear portion of the sole and the forepart of the sole, which angle varies with different styles of shoes. It is desired that the side units 16 be located substantially perpendicular to the line of tangency to the curved portion of the sole edge with which they are to come into engagement. As will be described, the angular positions of the side units are adjustable and also are reversible without adjustment so as to utilize the machine for the operation upon left and right shoes by the same mechanism. Since both units are similar in construction, only one will be described in detail. Each unit has a casing 290 (Fig. 13) provided at its inner end with alined lugs 292 which are pivotally secured by means of fulcrum studs 294 (Figs. 1 and 4) to a U-shaped carrier bracket 296. Of course, there is one carrier bracket 296 for each unit 16. Each bracket 296 is pivotally connected at the upper and lower ends of its forward portion by studs 298 to lugs on the fixed bracket 12 of the machine frame 14. Considering the left-hand bracket 296 (as viewed from the front of the machine), the upper end of its forward portion has integral therewith an arm 300 (Fig. 4) which extends laterally and to the right of the machine. The arm 300 is connected by a pivot pin 302 and a swivel block 304 (Fig. 1) to a link 306 extending forwardly of the machine and connected by a pivot pin 308 (Fig. 4) to an arm 310. The arm 310 has a hub 312 which is mounted for free rotation on a shaft 314 rotatably mounted in the bracket 12 of the machine

frame. The hub 312 is surrounded by a torsion spring 316, one end of which lies against a lateral projection of the arm 310 and the other end of which is held in an adjustment disk 318 which bears against the hub of the previously mentioned arm 130 and is connectable therewith. Rotation of the disk 318 with relation to the hub of the arm 130 effects an adjustment of the tension of the torsion spring 316. The hub of the arm 130 is keyed to the shaft 314. Accordingly, on operation of the arm 130 as previously described, the arm 310 is yieldingly operated through the torsion spring 316 to rotate the left-hand bracket 296 about the studs 298 and to move its side unit 16 as will be described more in detail.

The right-hand carrier bracket 296 (as viewed from the front of the machine) has integral with it at the lower end of its forward portion an arm 320 (Fig. 4) which extends laterally and to the left of the machine. A link 322 connects the arm 320 to an arm 324 which corresponds to the just-described arm 310. The arm 324 also has a hub 326 mounted for free rotation on the shaft 314 and carrying a torsion spring 328, one end of which lies against a lateral projection of the arm 324 and the other end of the spring being held in an adjustment disk 330 corresponding to the disk 318 and being connectable with another disk 331 fixed on the left-hand end (Fig. 4) of the shaft 314. Again rotation of the disk 330 with relation to the disk 331 serves the purpose of adjusting the tension of the torsion spring 328. Both the arms 310 and 324 have forwardly extending abutments 332 and 334 which cooperate with stop arms 336 and 338 fast on the shaft 314.

Thus, on power operation of the arm 130 (that is, counterclockwise rotation as viewed in Fig. 1) the shaft 314 is positively rotated but the arms 310, 324, through the agency of which the side units 16 are moved into engagement with the work by means of the arms 300, 320 which with their respective brackets 296 form quasi bell-crank levers, are yieldingly operated by the torsion springs 316, 328 so that they not only yieldingly engage the work but after engagement remain stationary while the shaft 314 may continue its rotation, it being understood that the stroke of the arm 130 is constant.

The side units 16 are adjustable prior to their power operation with relation to the work support or still better with relation to the shoe mounted on the work support to either shorten or lengthen their operative movements into engagement with the work as conditions may require it. As already stated, the angular positions of the side units 16 also are adjustable or reversible to accommodate shoes of different swings and to accommodate left and right shoes. The adjustment of the side units 16 toward and from the shoe on the work support 10 is accomplished by utilizing the actuating mechanism just described, that is, by manually rotating the shaft 314. It will be recalled that the arm 130 has a tapped bushing in which is rotatable the threaded portion of the rod 128 (Fig. 1). The forward end of the rod 128 has a swivel connection with a link 340 extending into a sleeve 342. The link 340 has a lateral pin 344 which engages a slot provided in the sleeve 342. Thus the link 340 can move axially with relation to the sleeve but is constrained to rotate with the sleeve upon rotation of the latter. The sleeve 342 has a swivel connection at its forward end to a short shaft 346 rotatable in a fixed bearing 348 and carrying

a hand wheel 350. During the power operation of the arm 130 the link 340, of course, is moved axially and this movement takes place with relation to the sleeve 342 which is then stationary, the pin 344 moving along the slot in the sleeve 342. The adjustment of the side units 16 toward and from the work on the work support takes place when the power-operated mechanism is inoperative, in which case the arm 124 carrying the rear end of the rod 128 is stationary so that on rotation of the sleeve 342 by the hand wheel 350 the arm 130 is rotated in one direction or the other, thereby rotating the shaft 314 and through the agency of the arms 310 and 324 adjusting the side units 16 as desired. It should be added that during this adjustment the carrier brackets 296 are rotated about their fulcrum studs 298, thus carrying the side units 16 bodily inwardly or outwardly of the supported shoe.

The mechanism for effecting the angular adjustment of the side units 16 will now be described. This adjustment of the side units takes place about the fulcrum studs 294 as centers. Each unit 16 is angularly adjusted by a rod 352 (Figs. 6, 7 and 13), each rod having a ball-and-socket connection 354 with its respective side unit 16. Considering first the right-hand unit 16 (Fig. 6), the front end of its rod 352 has a pivotal connection with an arm 356 (Fig. 7). The arm 356 is part of a two-armed lever having spaced hubs 358 (Fig. 8) and having another arm 360 extending from the lower hub 358 toward the left of Fig. 8. This two-armed lever is mounted for free rotation on a shaft 362 which is in bearings in a bracket 364 secured to the fixed bracket 12. The previously mentioned bearing 348 is formed on the bracket 364. The arm 356 carries a spring-pressed plunger 368 having a hand knob 370 and adapted to engage holes 372 (Fig. 7) provided in a plate 374 secured to a portion of the bracket 364.

Considering now the left-hand unit 16 (Fig. 6), the front end of its rod 352 is pivotally connected to an arm 376 (Figs. 7 and 8) which is freely rotatable on the shaft 362. The arm 376 carries a spring-pressed plunger 378 having a hand knob 380 and adapted to engage holes 382 (Fig. 7) provided in a plate 384 secured to the arm 360 which is a part of the above-described two-armed lever.

In adjusting the side units 16 angularly to accommodate shoes of different styles and swings, it will be necessary to adjust the right-hand unit 16 (Fig. 6) first by lifting the spring-pressed plunger 368 by means of the hand knob 370 and moving the arm 356 with relation to the plate 374 containing the adjustment holes 372, since that adjustment also results in a corresponding adjustment of the arm 376 connected to the left-hand unit 16, the arm 376 being connected by the spring-pressed plunger 378 to the arm 360 which is integral with the arm 356. Accordingly, after the right-hand unit 16 has been adjusted to its proper angular position, it will be necessary to lift the plunger 378 by means of the hand knob 380 and move the arm 376 with relation to the now stationary arm 360 so as to adjust the left-hand unit 16.

The same adjusting mechanism may be utilized when adjusting the side units 16 from operation on right shoes to left shoes or vice versa, which adjustment, provided the left and right shoes are of the same style, will require merely a reversal of the angular positions of the side units. To this end, the bracket 364 has a forwardly extending portion 390 (Figs. 7 and 8) which is cup-

shaped and contains a hollow hand knob 392 of substantially cylindrical shape. The hand knob 392 carries a substantially oval-shaped stop 394 which may be adjusted by the hand knob to various angular positions, these positions being determined by a pin (not known) on the lower portion of the knob, the pin engaging four positioning holes 396 (Fig. 7) in the bottom of the cup. The hand knob 392 is normally held down by a spring (not shown) which is located inside the knob 392 on a screw bolt 398. The bolt 398 extends through a central hole in the bottom of the cup upwardly into the knob 392 and is held in place by a nut 400 (Fig. 8). The just-mentioned spring is confined between an inner shoulder of the knob 392 and the head of the bolt 398 and thus tends to hold the knob 392 down. The knob is raised manually against the pressure of its spring to remove the positioning pin out of one of the holes 396 whereupon the knob 392 may be rotated to change the position of the stop 394. The stop 394 is adapted to be engaged on its right-hand side (Figs. 7 and 8) by an abutment screw 402 carried in a forward extension 404 of the arm 356. The left-hand side of the stop 394 is adapted to be engaged by an abutment screw 406 carried in a forward extension 408 of the arm 376. Thus, the movements of the arms 356 and 376 forwardly of the machine are limited by the stop 394. Since, as Fig. 6 illustrates, one of the side units 16 assumes an angular position with relation to the longitudinal median line of the work support different from the angular position of the other unit, the arrangement is such that in the proper position of both side units 16, one of the abutment screws 402, 406 is engaging the abutment 394, whereas the other screw is located a predetermined distance from the stop 394 (see Fig. 7). The adjustment illustrated in Fig. 7 is for a left-hand shoe. The angularity of the left-hand side unit 16 is more pronounced than that of the right-hand unit 16 due to the more pronounced curvature of the left-hand edge of the sole forepart. The abutment screw 402 rests against the stop 394 whereas the screw 406 is located a certain distance therefrom. When it is now desired to operate upon a right-hand shoe corresponding to the illustrated left-hand shoe it is merely necessary to raise the spring-pressed plunger 368 by its hand knob 370 out of its hole 372 and shift the arm 356 until the screw 406 abuts the stop 394, in which case the angular positions of the side units 16 are reversed in the sense that the right-hand side unit now assumes the more pronounced angular position and the left-hand unit the less pronounced angular position. The plunger 368, in the new position, reengages another adjustment hole 372. The adjustment of the stop 394 illustrated in Fig. 7 may be maintained as long as the shoes to be operated upon are of similar style or swing. Should there be a substantial change of style or swing it would be necessary to change the angular position of the stop 394. It will be understood that for the operation upon shoes of extreme styles and swings the oval-shaped stop 394 will be positioned with its smallest diameter in line with the abutment screws 402, 406. This permits a substantial movement of the screws toward and from the stop 394, a substantial movement being necessary in view of the change from one extreme angular position of the side unit to its reverse position. On the other hand, if the run of shoes to be operated upon is of

less extreme style and swing, particularly if the angular disposition of the longitudinal median lines of the rear part and forepart of the shoe sole is less pronounced, it will be necessary to adjust the stop 294 so that particularly in the other extreme case of the least extreme style, the longest diameter of the stop is in alignment with the abutment screws 492, 496. Thus, it will be seen that for reversing the mechanism from operation on left shoes to right shoes or vice versa it is only necessary, provided the stop 294 is properly adjusted, to shift the arm 356 with relation to the plate 374 containing the adjustment holes 372. This moves the abutment screw which at that time is in contact with the stop 294 away from the stop a distance corresponding to the spacing of the other screw from the stop and corresponding to the length of movement of that other screw into engagement with the stop.

Each side gripper 18 has two jaws 410 and 412 (Figs. 13 and 14) pivotally secured in a bracket 414 by a pivot stud 416. The bracket 414 is secured to the inside of the casing 290 of the side unit 16. The upper jaw 410 has a tail 418 which carries a screw 420 engaging a plunger 422 movably mounted in a bore provided in the bracket 414 and supported by a heavy spring 424 seated in the bore. Moreover, the jaw 410 has a downwardly extending abutment 426 which, under the action of the spring 424, is forced against a stop 428 secured to the bracket 414. This permits the jaw 410 to yield slightly during the pulling-over operation. The lower jaw 412 is freely rotatable about the stud 416 and is pivotally connected by a link 430 to a swinging segment 432 pivoted at 434 to the bracket 414. The segment 432 in turn is pivotally connected by a link 436 to an arm 438 clamped on a shaft 440, the shaft being rotatably mounted in a bearing provided in the lower portion of the casing 290. The left-hand end (Fig. 13) of the arm 438 is connected by a ball and socket joint to the previously described rod 110 which is power-operated to close and open the side gripper. More specifically, on elevation of the rod 110 the lower gripper jaw 412 is swung upwardly about the stud 416, thereby gripping the marginal portion of the upper against the jaw 410.

The already mentioned stapling mechanism 20 simultaneously acts as a clamp to seize and hold together the marginal portions of the shoe upper A and the sole B in readiness for the stapling mechanism to secure these marginal portions together by a staple. This clamping action takes place between a movable stapling head 442 (Figs. 13 and 14) and a movable anvil 444, the arrangement being such that the anvil engages the lower face of the projecting marginal portion of the sole whereas the stapling head 442 descends, in a direction inclined toward the plane of the shoe bottom, upon the marginal portion of the upper. The stapling head 442 constitutes a casing for the stapling mechanism proper, the head being slidably mounted in a guideway 446 provided in the upper portion of the casing 290 of the side unit 16. The stapling head 442 is normally depressed by a spring 448 against a fixed stop on the casing 290. The spring 448 is seated in a bore provided in the casing 290 and acts on a plunger 450 also mounted in that bore, the lower end of the plunger acting against a bracket 452 which is bolted to one side of the head 442. The stapling head 442 contains a wire feeding mechanism 454 (Fig. 13) of a type shown and described in the

application for United States Letters Patent Serial No. 689,175 filed August 8, 1946, in the name of Herman A. Imhof. The staple inserted by the stapling mechanism is formed in the stapling mechanism from this wire. The wire is drawn off from a reel 456 (Fig. 1) and conducted over guide rolls, such as the guide roll 458 shown in Fig. 1, to the wire feeding mechanism. It is understood that since there are two stapling mechanisms at opposite sides of the work support, two wire reels 456 are mounted on the machine frame in side-by-side relation. The wire-feeding mechanism serves to advance the wire into a staple-forming mechanism which is of the conventional type and primarily comprises an outside former 460 (Fig. 14) and an inside former 462. The wire is fed between the formers and then the leading portion of the wire, on movement of the outside former 460, is severed and bent over the inside former 462 into the shape of a staple. The formed staple is driven by a driver 466 through a throatpiece 464 into the work parts. The driver 466 is removably clamped to a driver bar 468 guided for reciprocating movement in the head 442. The outside former 460, as is customary in staple-forming mechanisms of this type, is slidable in a passage or guideway provided in the stapling head 442. The inside former 462 is in the form of a long bar pivoted at 470 to the head 442 and engaged by a flat spring 472 secured to the head 442. The spring 472 forces the inside former into its operative position in which it cooperates with the outside former in the formation of a staple. To permit the driving of the staple it is necessary to move the inside former 462 out of the path of movement of the staple and the driver and this end is accomplished by the driver bar 468 which, at a predetermined moment in its downward travel, engages a shoulder on the inside former 462 and cams the inside former out of the path of movement of the driver. On retraction of the driver the spring 472 automatically returns the inside former to its operative position.

As previously stated, the rod 150 serves to operate the stapling mechanism. As illustrated in Fig. 13, the upper end of the rod 150 is pivotally connected by a ball-and-socket joint to a two-armed lever 474 which is mounted to rotate freely on the shaft 440. This lever 474, by a single swinging motion in a clockwise direction as viewed in Fig. 13, actuates the various instrumentalities of the entire stapling mechanism in timed sequence. More specifically, the lever 474 elevates the anvil 444 into engagement with the lower face of the sole margin, actuates the wire-feeding mechanism 454, actuates the outside former 460 to cut the wire and form the staple, and finally actuates the driver 466 to insert the staple.

The right-hand end (Fig. 13) of the lever 474 is pivotally connected by a link 476 to a bell crank lever 478 which is secured on a shaft 480 rotatably mounted in bearings in the casing 290 of the side unit 16. The bell crank lever 478 has an upwardly extending arm which is pivotally connected by a curved link 482 to an arm 484 which carries the anvil 444 and which is mounted to swing about a stud 486 secured in the bracket 414.

Therefore, on actuation of the lever 474, as referred to above, the bell crank lever 478 is swung in a counterclockwise direction as viewed in Fig. 13, thereby rotating the shaft 480 and elevating the anvil 444. Since the upwardly ex-

tending arm of the bell crank lever 478 and the link 482 in fact constitute a toggle which is straightened when the anvil 444 is moved up into its sole engaging position, the toggle acts as a lock holding the anvil in its elevated operative position.

Moreover, there is secured to the shaft 480 a cam arm 490 having an enlarged free end portion which is provided at its opposite sides with cam tracks. On the outer face, as viewed in Fig. 13, there is a cam track 492 which, on rotation of the cam arm 490 in a counterclockwise direction, as viewed in Fig. 13, serves to actuate the wire-feeding mechanism 454. A roll running in this cam track is carried by an arm 494 of a bell crank lever which is mounted to rotate on a shaft 496 secured in the casing 290. The other arm 498 of the bell crank lever is connected by a link 500 to a small arm 502 of the ratchet drive for the wire feeding mechanism described in detail in the aforementioned Imhof patient application.

On the inner face of the enlarged end of the cam arm 490 there is provided a cam track 504 in which runs a cam roll carried by an arm 506 (Fig. 14) of a bell crank lever also mounted to swing on the shaft 496. The arm 506 is similar to and located behind the arm 494. The arm 506 is integral with an upwardly extending arm 508 which is pivotally connected by a link 510 to a bell crank lever 512 rotatably mounted on a stud 514 secured in the casing 290 and provided at the front end of its forwardly extending arm with teeth that engage a rack provided on the outside former 460. Rotation of the bell crank lever 512 in a counterclockwise direction, as viewed in Fig. 14, which is caused by the above-mentioned rotation of the cam arm 490, results in a downward movement of the outside former 460 with the results described.

For the purpose of actuating the driver 466 there is secured on the shaft 480 a small arm 516 (Fig. 13) which is pivotally connected by a link 518 to an arm 520 mounted to swing on a pivot stud 522 secured in the casing 290. The free end of the arm 520 is pivotally connected to a collar 524 which is mounted to slide on a rod 526 pivotally suspended from an arm 528 pivotally secured at 530 to the casing 290 and adapted to operate the driver 466. The free end 532 of the arm 528 is rounded and engages between projections 534 (Fig. 14) on the driver bar 468. The collar 524 is supported on a spring 536 mounted on the rod 526, the lower end of the spring resting against a washer 538 held on the lower end of the rod 526 by lock nuts 540. As will be readily seen, on rotation of the shaft 480 in a counterclockwise direction, as viewed in Fig. 13, the link 518 is lowered rotating the arm 520 in a counterclockwise direction (Fig. 13) and loading the spring 536 since the rod 526 is prevented from downward movement in view of the locking of the arm 528 from which it is suspended. The locking mechanism for holding the arm 528 immovable at that time comprises a locking block 542 secured on the arm 528 and engaged by the hook-shaped end of a two-armed pawl 544 pivotally secured at 546 to the casing 290. The right-hand end of the pawl 544 is pivotally connected to a downwardly extending rod 548 which passes through a sleeve 550 pivotally supported by the link 518. The lower portion of the rod 548 has secured thereto a collar 552 and moreover a spring 554, mounted on the rod 548, is interposed

between a fixed collar on the upper end of the rod 548 and the sleeve 550. As shown in Fig. 13, the collar 552 is initially spaced from the sleeve 550 a certain distance which has to be traversed by the sleeve 550 on downward movement of the link 518 before the rod 548 is pulled down to move the pawl 544 out of latching engagement with the block 542, thereby releasing the arm 528 to the force of the loaded spring 536 to actuate the driver. After the driving of the staple and the return of the arm 528 into initial position the pawl 544 is yieldingly moved into locking position by the spring 554.

Before initiating a cycle of operations the operator, if necessary, makes the various adjustments described in detail above, such as the adjustment of the initial position of the link 72 which elevates the work support 10, the adjustment both heightwise and lengthwise of the shoe of the heelrest 166, the adjustment of the toe gage 194 and concomitant adjustment of the toe gripper 22, and the widthwise as well as angular adjustments of the side units 16 in accommodation of the length, width, style and swing of the shoe to be operated upon. Having done this he initiates the first portion of one cycle of operations by the depression of the treadle 58, thereby imparting, as described, to the cam shaft 38 one-half of a revolution. During this one-half of a revolution of the cam shaft 38 the link 90 is yieldingly moved to the right of Fig. 2 by its respective cam-operated actuating mechanism and the rods 110 at opposite sides of the work support are elevated, thereby closing the toe gripper 22 and both side grippers 18. It is understood, of course, that before the grippers are closed the operator has inserted the free marginal portion of the shoe upper A between the gripper jaws. The grippers having been closed, the link 72 is elevated by its respective cam-operated actuating mechanism, thereby elevating the work support 10 to perform the pulling-over operation as described, it being understood that this movement of the work support 10 takes place with relation to the grippers 18 and 22 which remain stationary while holding the margin of the upper gripped. Depending upon the initial adjustment of the link 72 the elevation of the work support takes place with a heelward or toeward component of movement or without any such components of movement which primarily affects the operation of the toe gripper as will be readily understood. It has been found desirable to impart to the upper during the elevation of the work support a tensioning stress in the longitudinal direction of the last and toewardly thereof to insure a complete tensioning of the shoe upper over the entire forepart of the last. However, before securing together the marginal portion of the tensioned upper and the projecting marginal portion of the sole at the opposite sides of the forepart by the staples driven by the side units 16 it is desirable to release the toe gripper to prevent the top of the vamp portion of the upper from "bridging" the frequently somewhat concave top of the last forepart. It is for this reason that the toe gripper, before the first portion of the cycle of operations is terminated, is opened again to release the upper which, at the termination of the first portion of the cycle, is then held only by the side grippers. The machine comes automatically to a stop at the end of the first portion of the machine cycle to enable the operator to inspect the result of the pulling-over operation. If the operator is satisfied with the pulling-over operation he then initiates the second portion of the

cycle by retreading the machine. During the second portion of the cycle the cam shaft 38 is rotated through the second half of one complete revolution and as a result of this rotation the side units 16 are swung in. The margins of the upper and sole are engaged between the upwardly moving anvil 444 and the stapling head 442, and in view of the yieldable mounting of the staple head 442 the head can adjust itself automatically to variable thicknesses of the combined margin of the upper and the sole. The margin of the sole and the upper having been clamped, the side grippers are opened to release the upper, and in the meantime, as a result of the rotation of the lever 474, the wire-feeding mechanism 454 has been operated to advance the wire into the staple-forming mechanism, the outside former 460 then being lowered to sever the wire and form the staple. Finally on engagement of the sleeve 550 with the collar 552, after having traversed the lost motion provided between it and the collar and after the driver-actuating spring 536 has been loaded as described, the arm 528 is released to the force of the loaded spring 536 with the result that the formed staple is driven out of the throat 464 through the combined margins of the upper and the sole, the ends of the staple legs being clinched against the anvil 444 supporting the work from beneath. Toward the end of the second portion of the cycle the various described instrumentalities are then returned by their respective cam-operated mechanisms into their initial positions in readiness for the operation upon the next shoe.

Having thus described the invention, what is claimed as new and desired to be secured by Letters Patent of the United States is:

1. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for effecting relative movement of the support and the grippers heightwise of the last to pull the upper over the last, means movable in a direction inclined toward the plane of the shoe bottom for clamping the margin of the pulled-over upper against the sole, and fastening inserting means for securing the margin of the upper to the sole.

2. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for imparting to the support movement in a direction heightwise of the last to pull the upper over the last, means movable in a direction inclined toward the plane of the shoe bottom for clamping together the margins of the upper and the sole, a fastening inserting mechanism, and means for actuating the fastening inserting mechanism to insert fastenings securing the upper to the sole.

3. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for effecting relative movement of the support and the grippers heightwise of the last to pull the upper over the last, means for

clamping the margin of the pulled-over upper against the sole, means for opening the toe gripper before the margin of the upper is thus clamped, and fastening inserting means for securing the margin of the upper to the sole.

4. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for effecting relative movement of the support and the grippers heightwise of the last to pull the upper over the last, means for clamping the margin of the pulled-over upper against the sole, means for inserting fastenings to secure the margin of the upper to the sole, and means for operating said toe and side grippers to release the upper at predetermined different times in the operation of said clamping means.

5. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for effecting relative movement of the support and the grippers heightwise of the last to pull the upper over the last, means for clamping the margin of the pulled-over upper against the sole, means for opening the toe gripper before the margin of the upper is thus clamped, fastening inserting means for securing the margin of the upper to the sole, and means for opening the side grippers before the margin of the upper is secured to the sole.

6. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for imparting to the support movement in a direction heightwise of the last to pull the upper over the last, means for clamping together the margins of the upper and the sole, means for opening the toe gripper before the margins of the upper and the sole are clamped together, a fastening inserting mechanism, and means for actuating the fastening inserting mechanism to insert fastenings securing the upper to the sole.

7. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for imparting to the support movement in a direction heightwise of the last to pull the upper over the last, means for clamping together the margins of the upper and the sole, means for opening the toe gripper before the margins of the upper and the sole are clamped together, a fastening inserting mechanism, means for actuating the fastening inserting mechanism to insert fastenings securing the upper to the sole, and means for opening the side grippers before the fastenings are inserted.

8. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated

mechanism for effecting relative movement of the support and the grippers heightwise of the last to pull the upper over the last, means for clamping the margin of the pulled over upper against the sole, and fastening inserting means associated with the side grippers for securing the margin of the upper to the sole.

9. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for imparting to the support movement in a direction heightwise of the last to pull the upper over the last, means associated with the side grippers for clamping together the margins of the upper and the sole, and fastening inserting means for securing the margin of the upper to the sole.

10. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for imparting to the support movement in a direction heightwise of the last to pull the upper over the last, means associated with the side grippers for clamping together the margins of the upper and the sole, means for opening the toe grippers before the margins of the upper and the sole are clamped together, and fastening inserting means also associated with the side grippers for securing the margin of the upper to the sole.

11. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for imparting to the support movement in a direction heightwise of the last to pull the upper over the last, means associated with the side grippers for clamping together the margins of the upper and the sole, means for opening the toe grippers before the margins of the upper and the sole are clamped together, fastening inserting means also associated with the side grippers for securing the margin of the upper to the sole, and means for opening the side grippers before the margin of the upper is secured to the sole.

12. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for moving the support in a direction heightwise of the last from an adjustable initial position to a fixed elevated position to pull the upper over the last, means for clamping together the margins of the upper and the sole, a fastening inserting mechanism, and means for actuating the fastening inserting mechanism to insert fastenings securing the upper to the sole.

13. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for moving the support in a selected

direction heightwise of the last from an adjustably variable initial position to a fixed elevated position to pull the upper over the last, means for clamping together the margins of the upper and the sole, a fastening inserting mechanism, and means for actuating the fastening inserting mechanism to insert fastenings securing the upper to the sole.

14. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for moving the support in a direction heightwise of the last to pull the upper over the last, means for adjusting the initial position of the work support to vary the direction of movement of the work support into a fixed elevated position, thereby varying the extent of lengthwise pull imparted to the upper, means for clamping together the margins of the upper and the sole, a fastening inserting mechanism, and means for actuating the fastening inserting mechanism to insert fastenings securing the upper to the sole.

15. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for moving the work support in a direction heightwise of the last into a fixed elevated position to pull the upper over the last, said mechanism including parts relatively adjustable to vary the direction of said movement and thus to vary the extent of lengthwise pull imparted to the upper, means for clamping together the margins of the upper and the sole, a fastening inserting mechanism, and means for actuating the fastening inserting mechanism to insert fastenings securing the upper to the sole.

16. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for moving the support in a direction heightwise of the last to pull the upper over the last, means for adjusting the initial position of the work support to cause it to have a component movement heelward of the last during its heightwise movement, means for clamping together the margins of the upper and the sole, and a fastening inserting mechanism adapted to drive fastenings securing together the margins of the upper and the sole.

17. In a machine for working shoe uppers over lasts, a support for a last with a sole and an upper thereon, side grippers for seizing the margin of the upper at opposite sides of the forepart of the last, a toe gripper for seizing the margin of the upper at the toe end of the last, power-operated mechanism for moving the support in a direction heightwise of the last to pull the upper over the last, means for determining the direction of said heightwise movement to cause the work support to have a component movement lengthwise of the last during its heightwise movement to increase the extent of the lengthwise pull imparted to the upper, means for clamping together the margins of the upper and the sole, and a fastening inserting mechanism adapt-

ed to drive fastenings securing together the margins of the upper and the sole.

18. In a machine for working shoe uppers over lasts, a support for a last with a sole and an upper thereon, side grippers for seizing the margins of the upper at opposite sides of the forepart of the last, a toe gripper for seizing the margin of the upper at the toe end of the last, power-operated mechanism for moving the support in a direction heightwise of the last to pull the upper over the last, means for adjusting the initial position of the work support to cause it to have a component movement toward the last during its heightwise movement, means for clamping together the margins of the upper and the sole, and a fastening inserting mechanism adapted to drive fastenings securing together the margins of the upper and the sole.

19. In a machine for working shoe uppers over lasts, a support for a last with a sole and an upper thereon, grippers for seizing the margin of the upper, a link for elevating the support to pull the upper over the last, a guide member for that link, a pivot about which the guide member is adjustable, a sliding connection between the link and the guide member, and means for so operating the link that at the end of its operative stroke the sliding connection is positioned in alignment with said pivot.

20. In a machine for working shoe uppers over lasts, a support for a last with a sole and an upper thereon, grippers for seizing the margin of the upper, a link for elevating the support to pull the upper over the last, a guide member for that link, a connection between the link and the guide member, the connection being movable with relation to the guide member on elevation of the work support, means for moving the connection to a predetermined fixed point so as to elevate the work support, and means for adjusting the guide member about said fixed point.

21. In a machine for working shoe uppers over lasts, a support for a last with a sole and an upper thereon, grippers for seizing the margin of the upper, a heelrest on the support, a toe gage on the support, means for adjusting the heelrest and the toe gage in the longitudinal direction of the support and for adjusting the heelrest heightwise of the support, and means for elevating the work support to pull the upper over the last.

22. In a machine for working shoe uppers over lasts, a support for a last with a sole and an upper thereon, side grippers and a toe gripper for seizing the margin of the upper, a toe gage on the support, means for simultaneously adjusting the toe gage and the toe gripper in the longitudinal direction of the support, and means for elevating the work support to pull the upper over the last.

23. In a machine for working shoe uppers over lasts, a support for a last with a sole and an upper thereon, side grippers and a toe gripper for seizing the margin of the upper, a heelrest on the support, a toe gage on the support, means for adjusting the heelrest in the longitudinal direction of the support, means for simultaneously adjusting the toe gage and the toe gripper in the longitudinal direction of the support, and means for elevating the support to pull the upper over the last.

24. In a machine for working shoe uppers over lasts, a support for a last with a sole and an upper thereon, side grippers and a toe gripper for seizing the margin of the upper, a heelrest on the support, a toe gage on the support, means for adjusting the heelrest in the longitudinal direction of the support, means for simultaneously adjusting the toe gage and the toe gripper in the longitudinal direction of the support, and means for elevating the support to pull the upper over the last.

on the support, a toe gage on the support, means for adjusting the heelrest in the longitudinal direction and heightwise of the support, means for simultaneously adjusting the toe gage and the toe gripper in the longitudinal direction of the support, and means for elevating the support to pull the upper over the last.

25. In a machine for working shoe uppers over lasts, a support for a last with a sole and an upper thereon, grippers including side grippers and toe grippers for seizing the margin of the upper around the forepart of the last, power-operated mechanism for moving the support heightwise of the last to pull the upper over the last, means comprising a sole-engaging member and an upper-engaging member for clamping together the margins of the upper and the sole, means for positively moving the sole-engaging member into clamping position, means for yieldingly moving the upper-engaging member into clamping position, and fastening inserting means adapted to secure together the margins of the upper and the sole.

26. In a machine for working shoe uppers over lasts, a support for a last with a sole and an upper thereon, grippers including side grippers and toe grippers for seizing the margin of the upper around the forepart of the last, power-operated mechanism for moving the support heightwise of the last to pull the upper over the last, means comprising a sole-engaging member and an upper-engaging member for clamping together the margins of the upper and the sole, means for positively moving the sole-engaging member into clamping position, means for locking the sole-engaging member in clamping position, means for yieldingly moving the upper-engaging member into clamping position, and fastening inserting means adapted to insert fastenings to secure together the margins of the upper and the sole.

27. In a machine for working shoe uppers over lasts, a support for a last with a projecting sole and upper thereon, grippers, including side grippers, for seizing the margin of the upper, power-operated mechanism for effecting relative movement of the support and the grippers heightwise of the last to pull the upper over the last, stapling mechanisms associated with the side grippers and comprising each a sole-engaging anvil, wire-feeding mechanism, staple-forming mechanism, staple-inserting means and a throat, and a single member adapted to move the anvil to clamp the margins of the upper and the sole against the throat and to operate the wire feeding mechanism, the staple-forming mechanism and the staple-inserting means in timed sequence.

28. In a machine for working shoe uppers over lasts, a support for a last with a projecting sole and upper thereon, grippers, including side grippers, for seizing the margin of the upper, power-operated mechanism for effecting relative movement of the support and the grippers heightwise of the last to pull the upper over the last, stapling mechanisms associated with the side grippers and comprising each a sole-engaging anvil, wire-feeding mechanism, staple-forming mechanism, a staple-inserting driver and a throat, and a single member adapted to move the anvil to clamp the margins of the upper and the sole against the throat and to cause it to be held locked in clamping position, and simultaneously to operate the wire-feeding mechanism and thereafter to operate the staple-forming mechanism and finally the driver.

29. In a machine for working shoe uppers over lasts, a support for a last with a projecting sole and an upper thereon, grippers including side grippers, for seizing the margin of the upper, power-operated mechanism for effecting relative movement of the support and the grippers height-wise of the last to pull the upper over the last, stapling mechanism associated with the side grippers and comprising each a sole-engaging anvil, wire-feeding mechanism, staple-forming mechanism and a yielding stapling head including a driver, and a power-operated lever adapted to move the anvil to clamp the margins of the upper and the sole against the head causing the latter to yield to an extent depending upon the combined thicknesses of said margins, and simultaneously to operate the wire-feeding mechanism and thereafter to operate the staple-forming mechanism and cause the driver to insert a staple through the margins of the upper and the sole and to clinch the staple against the anvil.

30. In a machine for working shoe uppers over lasts, a support for a last with a projecting sole and an upper thereon, grippers, including side grippers, for seizing the margin of the upper, power-operated mechanism for effecting relative movement of the support and the grippers height-wise of the last to pull the upper over the last, stapling mechanisms associated with the side grippers and comprising each a sole-engaging anvil, wire-feeding mechanism, staple-forming mechanism including a movable inside former and a movable outside former, and staple-inserting mechanism including a yielding throat and a driver, and a single power-operated member adapted to move the anvil to clamp the margins of the sole and the upper against the throat and simultaneously to operate the wire-feeding mechanism, thereafter to move the outside former with relation to the inside former so as to sever the fed-in extent of wire and form a staple and then to operate the driver causing the latter to insert the staple through the margins of the upper and the sole, thereby also causing the inside former to be moved with relation to the outside former.

31. In a machine for working shoe uppers over lasts, a support for a last with a projecting sole and an upper thereon, grippers, including side grippers, for seizing the margin of the upper, power-operated mechanism for effecting relative movement of the support and the grippers height-wise of the last to pull the upper over the last, stapling mechanisms associated with the side grippers and comprising each a sole-engaging anvil, wire-feeding mechanism, staple-forming mechanism including a movable inside former and a movable outside former, and staple-inserting mechanism including a yielding throat, a spring-operated driver and a releasable latch holding the driver against the force of its spring, and a single power-operated member adapted to move the anvil to clamp the margins of the sole and the upper against the throat and simultaneously to operate the wire-feeding mechanism and load the driver-operating spring, thereafter to move the outside former with relation to the inside former so as to sever the fed-in extent of wire and form a staple, and then to release the latch to permit operation of the driver by its spring thereby inserting the staple through the margins of the upper and the sole and simultaneously camming out the inside former.

32. In a machine for working shoe uppers over lasts, a support for a last with a sole and an

upper thereon, side grippers and a toe gripper for seizing the margin of the upper, mechanism for elevating the support to pull the upper over the last, means for operating the grippers, means for clamping the margins of the pulled-over upper and sole together, fastening inserting means for inserting fastenings through the clamped margins of the upper and the sole, power-operated mechanism for actuating said support-elevating mechanism, the gripper-operating means, the clamping means and the fastening inserting means, and means causing said power-operated mechanism to run first through one-half of one cycle during which half the gripper-operating means is actuated to close the grippers, the support-elevating mechanism is operated and then the toe gripper is opened, and then through the other half of the cycle during which other half the clamping means is operated while the side grippers are opened and finally the fastening inserting means is operated.

33. In a machine for working shoe uppers over lasts, a support for a last with a sole and an upper thereon, side grippers and a toe gripper for seizing the margin of the upper, mechanism for elevating the support to pull the upper over the last, means for operating the grippers, means for clamping the margins of the pulled-over upper and sole together, fastening inserting means for inserting fastenings through the clamped margins of the upper and the sole, power-operated mechanism for actuating said support-elevating mechanism, the gripper-operating means, the clamping means and the fastening inserting means, and means causing said power-operated mechanism to run first through one-half of one cycle during which half the gripper-operating means is actuated to close the grippers, the support-elevating mechanism is operated and then the toe gripper is opened, then after a pause through the other half of the cycle during which other half the clamping means is operated while the side grippers are opened and finally the fastening inserting means is operated, and means adapted to render the fastening inserting mechanism inoperative during said second half of the cycle.

34. In a machine for working shoe uppers over lasts, a support for a last with a sole and an upper thereon, side grippers and a toe gripper for seizing the margin of the upper, mechanism for elevating the support to pull the upper over the last, means for clamping the margins of the pulled-over upper and of the sole together, fastening inserting means disposed at opposite sides of the support and associated with said side grippers and clamping means, means for positioning the fastening inserting means at predetermined angles, different from each other, with relation to the median longitudinal line of the support, and means for reversing the angular positions of the fastening inserting mechanisms.

35. In a machine for working shoe uppers over lasts, a support for a last with a sole and an upper thereon, side grippers and a toe gripper for seizing the margin of the upper, mechanism for elevating the support to pull the upper over the last, means for clamping the margins of the pulled-over upper and of the sole together, side units disposed at opposite sides of the support and supporting the side grippers and said clamping and fastening inserting means, means for moving the side units laterally of the support to carry the clamping and fastening inserting means into engagement with the shoe on the

327

elastom means for adjusting the extent of lateral movement of the side units into engagement with the shoe, means for locating the side units in a predetermined angular relation to the longitudinal median line of the support, and means for reversing the angular positions of the side units so as to adapt the machine for operation on left and right shoes.

GERTRUDE AKHOLMGREN,
Administratrix of the Estate of Eric A. Holmgren, Deceased.
